(57) CLAIM

The ornamental design for a glass mount support, as shown and described.

DESCRIPTION

FIG. 1 is a top right perspective view of a glass mount support in an environment of use showing our new design;

FIG. 2 is a top right perspective view thereof;

FIG. 3 is a front elevation view thereof;

FIG. 4 is a left elevation view thereof;

FIG. 5 is a rear elevation view thereof;

FIG. 6 is a right elevation view thereof;

FIG. 7 is a top plan view thereof;

FIG. 8 is a bottom plan view thereof;

FIG. 9 is a top left perspective view thereof;

FIG. 10 is a bottom left perspective view thereof; and,

FIG. 11 is a front perspective view thereof.

The broken lines in the figures represent environmental subject matter which forms no part of the claim.
